UNITED STATES PATENT OFFICE.

FREDERICK W. CLARK, OF ROCHESTER, NEW YORK, ASSIGNOR TO CLARK PAPER & MANUFACTURING COMPANY, OF ROCHESTER, NEW YORK, A CORPORATION OF NEW YORK.

CUSHION-PAD.

1,251,964.

Specification of Letters Patent. Patented Jan. 1, 1918.

Application filed May 28, 1917. Serial No. 171,553.

To all whom it may concern:

Be it known that I, FREDERICK W. CLARK, a citizen of the United States, residing at Rochester, in the county of Monroe and 5 State of New York, have invented certain new and useful Improvements in Cushion-Pads, of which the following is a specification.

The object of this invention is to provide a new and improved form of cushion pad to cover fruit which is packed in barrels, baskets, etc. The cushion pad is placed below and above the fruit or between the fruit and the bottom and the cover of the 15 barrel.

This and other objects of the invention will be fully illustrated in the drawings described in the specification and pointed out in the claims at the end thereof.

20 In the drawings,

Figure 1 is a perspective view of my improved cover shown partly in section.

Fig. 2 is a perspective view of a portion of one of the corrugated paper strips used 25 in making the cover cushion pad.

Fig. 3 is a cross section of my improved cushion pad in which one or more layers of paper are substituted for the layer of excelsior.

30 In the drawings like reference numerals indicate like parts.

In the drawings reference numeral 1 indicates the cushion pad which has a layer 2 of fine binding material such as excelsior, straw, Florida moss, paper waste, seaweed, etc., and a layer 3 of corrugated paper strips such as are shown at 4 in Fig. 2.

The combination of the layer of fine material such as excelsior, etc., and the layer 40 of corrugated paper strips is inclosed in the paper cover 5 which completely surrounds the material of the cushion with an overlapping joint as shown at 6. An extra thickness of cover paper as indicated at 7 45 is used to finish the cover. The overlapping joint which is naturally rough is

placed over the layer of corrugated paper and the single thickness which is naturally smooth is placed over the layer of fine material.

50 The layer of corrugated paper is made up preferably of narrow strips of waste material, the strips usually having a width of from $\frac{1}{8}$ " to $\frac{1}{4}$ ". The cushion is made with a thickness of about $1\frac{1}{2}$ " at the center and 55 somewhat less than that at the edge.

In use, the cushion is placed with the fine material against the fruit. The corrugated paper should not be placed against the fruit, for one or more pieces of it will 60 probably stand on edge and the edges of such pieces if brought into contact with the fruit will bruise or cut the fruit.

65 It has been found from experience that the combination of excelsior and corrugated paper as set forth above makes a cushion that is unusually soft and elastic, and is very effective in protecting fruit against injury and prevents bruising. The cushion does not mat down into a dead, lifeless 70 mass as will excelsior alone.

In Fig. 3, I have shown a modification of my cushion pad in which one or more layers of paper 8 are used instead of the excelsior. In either form the paper or the excelsior 75 serves to tie the pad together and hold it in shape.

I claim.

1. A cushion comprising a layer of binding material and a layer of corrugated paper strips suitably inclosed in a wrapper. 80
2. A cushion comprising a layer of binding material and a layer of corrugated paper placed thereon suitably inclosed in a wrapper. 85

In testimony whereof I affix my signature in presence of two witnesses.

FREDERICK W. CLARK.
